UNITED STATES PATENT OFFICE

FRANCES SAMUELS, OF FLUSHING, NEW YORK, ASSIGNOR TO SIEGFRIED BEHR, OF NEW YORK, N. Y.

DESIGN FOR A HAT SUPPORT

Application filed February 21, 1930. Serial No. 34,603. Term of patent 3½ years.

To all whom it may concern:

Be it known that I, FRANCES SAMUELS, a citizen of the United States, residing at 3614 N. 165th St., Flushing, L. I., in the county of Queens and State of New York, have invented a new, original, and ornamental Design for a Hat Support, of which the following is a specification, reference being had to the accompanying drawing, forming part thereof.

Fig. 1 is a front elevation of the hat support showing my new design.

Fig. 2 is a side elevation of Fig. 1 as seen from the right side.

Fig. 3 is a top plan of Fig. 1.

Fig. 4 is a perspective view of the hat support when attached to a shelf.

I claim:

The ornamental design for a hat support substantially as shown.

FRANCES SAMUELS.
